UNITED STATES PATENT OFFICE

2,362,435

CONCRETE MIXER

Louis G. Hilkemeier, Milwaukee, Wis., assignor to
 Chain Belt Company, Milwaukee, Wis., a corporation of Wisconsin

Application January 28, 1942, Serial No. 428,603

4 Claims. (Cl. 259—164)

The invention relates to concrete mixers, and more particularly to the so-called high-discharge type of truck-mounted concrete mixer, a generic example of which may be found in the prior U. S. Patent No. 2,045,532, granted June 23, 1936, on an application filed by John C. Merwin and Charles F. Ball. The present invention however, represents a further development of certain charging mechanisms devised by the said Ball, primarily for use in connection with the inclined-axis type of machine disclosed in the aforesaid patent, which mechanisms are fully set forth in U. S. Patents Nos. 2,265,751 and 2,265,752, each granted December 9, 1941, and in U. S. Patent No. 2,281,820, granted May 5, 1942.

Briefly, the last mentioned patents and application disclose a charging hopper structure for the open upper end of a rotatable inclined-axis mixing drum, said structure including a non-rotatable hopper and being mounted for reciprocatory movements toward and from the drum opening upon a shaft disposed axially of the drum and extending through its said opening to and through the rear inclined wall of the hopper. While in actual practice these constructions have been found quite efficient in the accomplishment of their intended purpose of rapidly inducting the concrete-making solids into the drum, at the same time the extension of the supporting shaft to and through the rear wall of the hopper, notwithstanding that its dimensions were nominal, impeded to some extent the flow of the materials down the inclined rear wall of the hopper toward which the materials naturally gravitate.

It is one of the principal objects of the present invention, therefore, to provide a charging hopper construction for a mixer of this type wherein the supporting shaft does not extend to the rear inclined wall of the hopper, thereby providing for the unobstructed passage of the materials along such rear hopper wall, to the end that the introduction of the concrete-making materials into the drum may be facilitated and the time therefor further reduced.

In addition to the non-rotatable hopper element, the constructions of the aforesaid Ball patents and application also included an intermediate annular member journaled upon the said non-rotating hopper and axially movable with it to and from a position in which its perimetric portion engaged with the portion of the drum surrounding the drum opening, in which position the said annulus rotated with the drum. It is a further object of the present invention to provide an improved bearing and seal construction for this annular member.

The said Ball application Serial No. 354,521 further disclosed a venting arrangement for the hopper, providing for the escape of air from the drum during the charging of the concrete-mak-

ing materials thereto through the hopper, and it is a still further object of this invention to provide an improved venting means for that purpose.

5 With the above and other objects in view which will appear as the description proceeds, the invention resides in the novel details of construction and combinations and arrangements of parts more fully hereinafter disclosed.

10 Referring to the accompanying drawings forming a part of this specification, in which like reference characters designate like parts in all the views:

Figure 1 is a longitudinal vertical sectional view, partly in elevation, of the upper rear end portion of a concrete mixer of the type referred to above, with a charging hopper construction in accordance with the present invention applied thereto;

15 Figure 2 is a cross sectional view, partly in elevation and upon a slightly larger scale, of the parts shown in Figure 1, taken approximately on the plane indicated by the line 2—2 of Figure 1, looking in the direction of the arrows;

20 Figure 3 is an elevational view of the hopper structure per se, partly broken away and without the intermediate annulus, as seen from the left of Figure 1;

25 Figure 4 is an elevational view of the intermediate annular member per se, as seen from the right in Figure 1; and

30 Figure 5 is an enlarged cross sectional view through the improved bearing and seal between the hopper structure and intermediate annulus.

35 Referring more particularly to the said drawings there is illustrated, for the purposes of the present disclosure but not by way of limitation, the rear end portion of a mixing drum 10, of a "high-discharge" truck-mounted concrete mixer 40 of the type exemplified in the aforesaid patents, which drum is mounted in a framework 11 for rotation about an axis inclined to the horizontal by any suitable well-known means, not shown. The end of the drum is provided with the material-transfer opening 12 which has associated with it a charging hopper structure similar in certain respects to that disclosed in the said Ball patents and application, which structure may be mounted by the drum 10 for reciprocating movements in the direction of the drum axis to and from said material-transfer opening 12. The movements away from the drum or toward the right from the positions shown in Figure 1, are for the purpose of permitting discharge of the mixed concrete through the transfer opening 12, while the return movements to the positions shown are for the purpose of positioning the hopper structure to conduct a fresh charge of concrete-making materials, such as cement, sand

45 and gravel or crushed stone, through the opening

50 55 60

12 and into the drum where they will be transformed into the finished concrete mixture by the usual helical mixing blades 10' upon rotation of the drum. In this position the hopper structure also prevents discharge of the materials through the opening 12 during mixing.

The advantages of mounting the hopper structure upon the drum rather than upon the supporting framework 11 may be readily appreciated since such mounting maintains a constant relationship between or alinement of the drum and hopper structure, whereas if the hopper were mounted upon the framework 11, distortion of such framework due to the twisting and weaving movements of the truck chassis upon which the mixer unit is mounted, as it travels over rough ground, might misalign the drum and hopper to such an extent as to result in leakage of materials from the discharge opening during mixing and also possibly during charging, if the truck happened to be upon an uneven surface at that time.

As here shown, the hopper structure comprises a non-rotatable hopper 13 of more or less inverted coniform shape, the forward portion 14 of the wall of which is provided with a discharge port 15 through which the materials introduced through the open top of the hopper may pass into the drum by way of the transfer opening 12 of the latter, as will be readily understood from Figure 1. The opposite or rearward portion 16 of the hopper wall inclines sharply downwardly, substantially as shown in Figure 1, to the said discharge port 15 and since the action of gravity upon materials introduced into the hopper tends to cause such materials to seek and traverse this portion of the hopper wall, it is important from the standpoint of rapid charging of the materials into the drum that this portion of the wall be free from obstructions which would interfere with the movement of materials along it.

In order to provide a construction in which this rear wall is unobstructed and thus facilitate the charging of the materials, the present invention provides an annular element or collar 17 which is secured by welding or otherwise to the hopper around the discharge port 15 thereof and from the upper portion of the perimeter of which a supporting bracket 18 depends extending in a substantially radial direction to the axis of the discharge port 15. At this point the bracket 18 mounts a shaft 19 which extends forwardly from the bracket and is received within a pilot sleeve or bearing 20 which is supported by the drum 10 as, for instance, by means of the radially extending rods or tubes 21 rigidly secured to portions of the helical mixing blades 10', or directly to the shell of the drum, and to the said sleeve, as will be readily understood. In the construction shown the shaft 19 is rigidly attached to the bracket 18 and since the hopper structure does not rotate, the said shaft is journaled in the sleeve 20 so that the drum may rotate around it. On the other hand the shaft is axially slideable within the said sleeve so that the hopper structure may be moved away from the drum, or toward the right, as viewed in Figure 1, in order to permit discharge of the mixture, and subsequently return to the Figure 1 position to condition the apparatus for charging and mixing, as is fully disclosed in said prior Ball patents.

It will be noted that the shaft 19 extends into the hopper structure only approximately to the discharge port 15 and its end is materially

spaced from the inclined rear portion 16 of the hopper wall whereby it offers no interference to materials moving downwardly along said wall and into the drum. While the supporting bracket 18 blocks off a portion of the discharge port 15, such obstruction as may be imposed thereby to flow of the materials through said port occurs in an upper segment of the latter rather than along the sloping rear or bottom wall 16 of the hopper to which the materials naturally gravitate; and the impediment to the materials occasioned by the bracket is offset by the advantage resulting from the creation of a void forward of the bracket through which air may pass to the air vent, as will appear more fully below. Furthermore, the said bracket may be so shaped and dimensioned that its interference with the charging of the materials into the drum is appreciably less than is that of the shaft 19 and its bearing 20 when the said shaft is continued through to the wall portion 16, and as a result an appreciable decrease in the time for charging the materials into the drum may be accomplished through the use of the construction just described.

As above indicated the hopper 13 is non-rotatable, linkage 25 similar to that disclosed in the said Ball patents, Nos. 2,265,751 and 2,265,752, being provided between the hopper and frame 11 for preventing rotation while at the same time permitting reciprocation; and as in the said patents, the hopper element carries an intermediate ring member 26 journaled thereon for engagement with and rotation by the drum 10, when the parts are in the charging or mixing position illustrated in Figure 1. An annulus 17', of angular cross section, is rigidly carried by the collar 17 and one leg thereof conveniently forms one member of a journal bearing 36 for the ring member 26, the other or ring-carried member of which comprises an annulus 30, which is rigidly mounted upon the said ring member as by the bolts 31 and spacing bushings 32. A retaining ring 30', also secured by bolts 31, serves to maintain the intermediate ring assembly 26, 26', 30 in operative position on the annulus 17'.

The annulus 30 is provided with an annular recess 33 (see Figure 5) in which any suitable packing or sealing material 34 may be positioned and held snug against the member 17' by suitable means such as a coil spring 35, whereby to provide a labyrinth seal for protecting the bearing 36 against extraneous material. A grease fitting 37 may be provided, communicating through members 17 and 17' with the said bearing, to supply lubricant thereto.

In order to further protect this bearing against the entry of abrasive constituents of the concrete mixture thereto an additional seal is provided, comprising a resilient sealing ring 40, which is mounted upon the member 17', as will be clear from Figures 1 and 5. This sealing ring is provided with a plurality of outwardly extending circumferential ribs or flanges 41 which are axially spaced from one another to provide an annular space 42 between them. These flanges are constructed to extend straight out from the base ring 40, as indicated by broken lines of Figure 5, but in the assembly of the parts, they are engaged by the sealing annulus 26' which is rigidly carried by the ring member 26 and thereby caused to assume the curved or dished positions shown in Figures 1 and 5, both curving inwardly or forwardly toward the drum. With their outer peripheries in sliding engagement with the sealing annulus 26', pressure exerted upon either or both

of them in an outward direction, as by materials within the drum seeking to work outwardly, merely forces them more firmly against the inner surface of the annulus 26' and any tendency of the concrete materials to work past them is thus resisted very efficiently. The space 42 between the ribs 41 is preferably filled with grease by means of a grease fitting 45 and pipe 46, communicating with the said space, and the curved tensioned condition of the right hand flange 41 is likewise effective in resisting any tendency of such grease to work past it. Should there be any escape it would be towards the left as viewed in Figure 5, past the left hand flange 41 and into the drum.

In the said prior Ball application Serial No. 354,521 there was disclosed a means for venting the drum during charging, to prevent the building up of pressures therein during the charging operation. The present invention contemplates an improvement in this venting means, which as here shown, comprises a substantially rectangular shield 50 having side walls and a bottom wall, which shield is pivotally mounted as at 51 by a bracket 52 carried by the portion 14 of the hopper wall. This shield extends downwardly in front of the upper portion of the supporting bracket 18, its side and bottom walls being suitably conformed to the contour of the parts, and the said bracket 18 is provided with a venting aperture 54 which affords communication between the interior of the shield member 50 and the area forward of the said bracket where, as above indicated, a void is formed during charging. The upper end of the shield may be open as shown in Figure 1 and in addition thereto a vent opening 55 may be provided in the wall portion 14 to accommodate escape of air from the drum in the event the open upper end of the shield should become clogged. By pivotally mounting the shield on the bracket 52 the shield may be readily swung backwards, or counter-clockwise as viewed in Figure 1, for cleaning purposes should it become clogged with cement dust or other materials, and upon release it will drop to its original position where it will be maintained by the materials as they pass through the hopper. The non-rigid mounting of the shield also produces a tendency toward the automatic clearing of the vent through vibration of the parts when the machine is in use.

Any suitable means for reciprocating the hopper to and from its operative position may be provided, those here shown being similar to the means disclosed in the said Ball Patents Nos. 2,265,751 and 2,265,752 and including a manually operable shaft 60 carrying a pair of operating arms 61 extending downwardly, one to either side of the hopper 13. The lower ends of these said arms are connected through resilient or compressible connections 63 similar to those described in the said Ball patents to the trunnions 64 which are carried by arms 65 preferably formed as integral extensions of the collar 17, at either side thereof.

While for purposes of disclosure one form of the invention has been illustrated and described, it is obvious that those skilled in the art may vary the details of construction as well as the precise arrangement of the parts without depart-

ing from the spirit of the invention and therefore it is not wished to be limited to the above disclosure except as may be required by the claims.

5. What is claimed is:

1. In a concrete mixer, means for mounting a non-rotatable charging hopper upon a rotatable concrete mixing drum for reciprocatory movements toward and from a material-transfer opening in one end of said drum, said hopper having a discharge port co-operatively registerable with said drum opening for the transfer of materials from the hopper into the drum; said hopper mounting means comprising a collar structure secured to the hopper around said port and having a bracket member within said hopper extending across said port from the perimeter to the axis of the latter; means carried by said collar structure whereby the collar and hopper may be moved toward and from the drum opening; a shaft for supporting said hopper having one end portion mounted in said bracket in substantially the plane of said hopper port and projecting therefrom axially through said drum opening; and a bearing within and rotatable with the drum, slidably supporting the projecting portion of said shaft for movements axially of the drum.

2. An element for mounting a charging hopper upon a rotatable concrete mixing drum with the discharge port of the hopper in co-operative reciprocable relation to a material-transfer opening in an end of the drum, said element comprising an annular member securable to the hopper surrounding its discharge port and having a substantially radial bracket an arm extending from the perimeter of said member to its axis, the inner end of said bracket arm being formed to receive a portion of a hopper-supporting shaft mounted by the mixing drum axially of its transfer opening, said annular member also having oppositely disposed trunnions for connection to a hopper reciprocating means.

3. The combination with a charging hopper for concrete mixer drums, having a wall provided with a discharge port through which the concrete-making materials pass into the drum, of a shield member non-rigidly mounted in the hopper adjacent said wall and extending into said port sufficiently to provide a channel for the escape of air therethrough during the occupancy of the remainder of the port by materials passing through said hopper, the non-rigid mounting of said shield member providing for its vibratory agitation during operation of the apparatus to tend to automatically clear the channel of materials which may enter and deposit therein.

4. In a charging hopper for concrete mixer drums, having a wall provided with a discharge port through which the materials pass to the drum, a hopper supporting member having an apertured portion disposed within the area of said port; and means for venting the drum during charging comprising a shield member pivotally mounted adjacent said hopper wall, the upper portion thereof being in open communication with the atmosphere and the lower portion thereof of embracing the aperture in said supporting member.

CERTIFICATE OF CORRECTION.

Patent No. 2,362,435.

November 7, 1944.

LOUIS G. HILKEMEIER.

It is hereby certified that error appears in the printed specification of the above numbered patent requiring correction as follows: Page 3, second column, line 36, claim 2, after the word "bracket" strike out "an"; and that the said Letters Patent should be read with this correction therein that the same may conform to the record of the case in the Patent Office.

Signed and sealed this 13th day of February, A. D. 1945.

Leslie Frazer

(Seal)

Acting Commissioner of Patents.
